Filed March 31, 1939

FIG. 1

UNITED STATES PATENT OFFICE

2,312,011

EXPANSIBLE HONE

David A. Wallace, Detroit, Mich., assignor to
 Chrysler Corporation, Highland Park, Mich., a
 corporation of Delaware

Application March 31, 1939, Serial No. 265,109

6 Claims. (Cl. 51—184.1)

The present invention relates to the art of finishing surfaces such as cylindrical bores and comprises improvements in the structure of expandable hones and the means of operation thereof.

The invention comprises an expandable honing tool including a plurality of abrading elements, the tool being so constructed and arranged that the diameter of the tool may be increased after insertion of the tool into a bore by the application of fluid pressure whereby the abrading elements are held against the surface of the bore under fluid pressure, and in which the diameter of the tool may be reduced automatically in response to the release of fluid pressure whereby the tool may be withdrawn from the bore and inserted in another bore to be finished. The invention comprises the use of resilient, fluid-impervious expanding members operated by fluid pressure whereby even pressure may be exerted against the abrading elements throughout the extent of the work surface in order that a uniform finish may be accomplished. The principal object of the invention related above is achieved by simple, easily manufactured and assembled means.

Other objects and advantages of the invention will be apparent from a study of the following specification and accompanying drawing, wherein like numerals refer to like parts throughout. In the drawing Fig. 1 discloses a preferred form of my invention in operation; Fig. 2 is a horizontal section taken along line 2—2 of Fig. 1; and Fig. 3 is a horizontal section, similar to Fig. 2, of a modified form of hone.

In Figs. 1 and 2 there is disclosed a core structure 10 comprising a stem 11 and a body 12 having an integral flange 13 and a threaded shoulder 14. The flange 13 is at one end of the body portion 12 and a collar 15 of substantially the same diameter is slidably fastened to the lower end of the body 12 by a key 16. The flange 13 forms a fixed mounting means for one end of a hollow, resilient, fluid-impervious, substantially cylindrical expanding member 17 and the collar 15 forms a sliding mounting member for the other end of the expander 17. The relatively thin end portions of the expander 17 are conformed to embrace the flange 13 and collar 15 and the extreme ends of the expander are gripped against the outer end surfaces of flange 13 and collar 15 by locking members 18 and 19, so that the expander is fastened to the tool at its extreme ends, with the wall thereof free to move radially with respect to the longitudinal axis of the tool and with its lower end free to move

vertically in order to accommodate such radial movement.

The stem 11 and body portion 12 are longitudinally drilled to provide a passage 20, the upper end of which may be blocked by a chuck-connecting crossbar 21 passing through the stem. An intermediate portion of the stem is provided with a plurality of laterally extending inlets 22 and the intermediate portion of the body portion is provided with a plurality of lateral outlets 23, whereby a fluid may be forced through the interior of the core structure into the interior of the expanding member. Such fluid may be admitted through a running gland 25 comprising a non-rotatable collar 26 mounted between rotative collars 27 and 28 fixed to the stem 11. The fluid may be forced through a pipe 30 into an annular space 31 communicating with the inlets 22, which space is provided in the interior surface of a ring 33 mounted between the stem 11 and the running collar 26, and held in position by packing members 34 and 35. The pipe 30 may be connected to a source of fluid pressure (not shown) by a resilient connection permitting vertical movement of the tool, and since the stem 11 is free to rotate within the collar 25 the annular groove 31 will be at all times in communication with the interior of the core structure.

The expander 17 preferably comprises a substantially thick wall of fluid-impervious material such as soft rubber cured to a self-sustaining but resilient state. A plurality of rigid mounting bars 40 are imbedded in the wall of the expander, the bars being preferably equally spaced about the circumference of the expander and extending longitudinally thereof from a point adjacent the collar 13 to a point adjacent the collar 15. Abrading elements 41 are fixed to the mounting bars 40 so as to protrude beyond the surface of the expander 17, the abrading elements being preferably long and narrow and being formed of artificial material or natural stone commonly used for honing purposes. The surfaces of the mounting bars 40 may be adhered to the adjacent surfaces of the member 17 by any well-known process such as vulcanization.

Fig. 1 shows the honing member inserted within the cylindrical bore 45 of a cylinder block 46 and illustrates the use of the tool. The normal diameter of the tool (from the outer surfaces of diametrically opposite abrading elements) is preferably slightly less than the internal diameter of the bore 45 when the tool is in normal or non-expanded condition so that the tool may be inserted in the bore without difficulty. When the

tool is in position fluid may be admitted to the interior of the expander 17, whereupon uniform pressure will be exerted throughout the interior of the expander and each of the expanding elements will be caused to move radially outward to substantially the same extent under substantially the same pressure. The tool may now be rotated and vertically reciprocated, as is usual in the practice of finishing cylindrical bores. When the operation has progressed to a sufficient extent the fluid pressure may be released whereupon the expander 17 will automatically contract, permitting withdrawal of the tool.

In Fig. 2 the wall of the member 17 is shown as being substantially uniform in thickness, although pockets 47 may be formed therein between the mounting bars 41 in order to reduce the amount of material necessary.

In Fig. 3 the expander 17 is shown as being formed of a substantially thin wall of resilient material, the outer surface of which is substantially cylindrical but which is provided with a plurality of inwardly extending corrugations 50, to the outer surfaces of which are bonded the mounting bars 40. When fluid pressure is exerted against the interior surface of the form shown in Fig. 3, the abrading elements 41 will be moved outward uniformly under uniform pressure, and, in addition, the sides of the mounting bars 40 will be strongly gripped by the material comprising the corrugations 50 due to the exertion of pressure against the walls of the corrugations.

Having illustrated and described several embodiments of my invention it should now be apparent to those skilled in the art that the invention permits of various modifications in arrangement and details. All such modifications as come within the scope of the following claims are considered a part of my invention.

I claim:

1. An expansible hone for use in finishing cylindrical bores comprising a core structure having an inlet and an outlet for the passage of fluids therethrough, a running gland associated with said core structure and having a fluid passageway communicating with the interior of said core structure, a substantially cylindrical, resilient, hollow, fluid-impervious member mounted on said core structure and surrounding the outlet from said core structure, an abrading element supporting bar imbedded in the wall of said member and movable therewith as said member is expanded by fluid pressure transmitted through said fluid passageway, and a honing stone fixed to said bar and protruding beyond the surface of said member.

2. An expansible hone for use in finishing cylindrical bores comprising a core structure having an inlet and an outlet for the passage of fluids therethrough, a running gland associated with said core structure and having a fluid passageway communicating with the interior of said core structure, a substantially cylindrical, re-

silient, hollow, fluid-impervious member mounted on said core structure and surrounding the outlet from said core structure, a plurality of abrading element supporting bars imbedded in the wall of said member and movable therewith as said member is expanded by fluid pressure transmitted through said fluid passageway, and honing stones fixed to said bars and protruding beyond the surface of said member.

3. An expansible hone for use in finishing cylindrical bores comprising a core structure having an inlet and an outlet for the passage of fluids therethrough, a resilient, hollow, fluid-impervious, cylindrical shell mounted on said core structure and surrounding said outlet, and a plurality of abrading elements protruding from the surface of said shell and movable thereby in radial directions by expansion and contraction thereof in response to fluid pressure therein, said elements being spaced about the surface of said shell and extending substantially longitudinally thereof and parallel to the longitudinal axis of said core structure.

4. An expansible hone for use in finishing cylindrical bores comprising a core structure having an inlet and an outlet for the passage of fluids therethrough, a thick-walled, cylindrical shell of soft rubber mounted on said core structure and surrounding the outlet from said core structure, a plurality of rigid mounting bars imbedded in the wall of said shell, and a plurality of abrading elements carried by said bars and extending beyond the surface of said shell, said bars and elements being movable in radial directions by the expansion and contraction of said shell in response to fluid pressure therein.

5. An expansible hone for use in finishing cylindrical bores comprising a core structure having an inlet and an outlet for the passage of fluids therethrough, a thick-walled, cylindrical shell of soft rubber mounted on said core structure and surrounding the outlet from said core structure, a plurality of rigid mounting bars imbedded in the wall of said shell, and a plurality of abrading elements carried by said bars and extending beyond the surface of said shell, said bars and elements being movable in radial directions by the expansion and contraction of said shell in response to fluid pressure therein, said bars and elements extending longitudinally of said shell.

6. An expansible hone for use in finishing cylindrical bores comprising a core structure having an inlet and an outlet for the passage of fluids therethrough, a thin-walled, cylindrical shell of soft rubber mounted on said core structure and surrounding said outlet, said shell having a plurality of inwardly extending longitudinal corrugations, a mounting bar bonded to the outer surface of each of said corrugations, and an abrading element carried by each of said mounting bars and protruding beyond the surface of said shell.

DAVID A. WALLACE.
